UNITED STATES PATENT OFFICE.

HERMAN W. OSTER, OF CLEVELAND, OHIO, ASSIGNOR TO THE OSTER MANUFACTURING COMPANY, OF CLEVELAND, OHIO, A CORPORATION OF OHIO.

DIE-STOCK.

979,789.

Specification of Letters Patent. Patented Dec. 27, 1910.

Application filed May 14, 1909. Serial No. 495,890.

To all whom it may concern:

Be it known that I, HERMAN W. OSTER, a citizen of the United States, residing at Cleveland, in the county of Cuyahoga and State of Ohio, have invented a certain new and useful Improvement in Die-Stocks, of which the following is a full, clear, and exact description.

The object of this invention is to provide 10 a die stock adapted to be easily adjusted for cutting threads on pipes or other cylindrical bodies of different diameters, and tapering the threads which it cuts, and to be quickly disengaged from the work when the cutting 15 of the threads has been completed.

The invention consists primarily in the employment of a bar which extends across the tubular center of the die stock body so as to be struck and moved relatively to said 20 body by the end of the work which is being threaded, and means whereby said bar, when so moved, will throw a train of mechanism, substantially as shown, and compel the outward recession of said dies.

25 The invention also includes some minor features of novelty, among which may be specified the placement eccentrically on the bar which controls the position of a cam plate of a head, with the surface of said head 30 on one side thereof formed as a continuation of the corresponding surface of the bar.

A die stock embodying the invention is shown in the drawing and is hereinafter fully described both as to construction and mode 35 of operation, and the novel combinations of parts constituting the invention are definitely set forth in the appended claims.

In the drawing, Figure 1 is a front end view of a die stock embodying the invention: 40 Fig. 2 is a side elevation thereof. Fig. 3 is a longitudinal sectional view in the plane indicated by line 3—3 on Fig. 1. Fig. 4 is a fragmentary section on line 4—4 on Fig. 2. Fig. 5 is a fragmentary sectional view in the 45 plane on line 5—5 on Fig. 2.

Referring to the parts by letters, A represents the body of the die stock.

B, B, represent the radially movable dies mounted in guideways in the head or 50 enlarged front end of said body.

C represents a cam plate, rotatably mounted on the end of the body, and having the usual scrolls, indicated by dotted lines in Fig. 1, for engagement with the dies to 55 move them radially inward or outward.

D represents a cap secured to the front end of the body and serving primarily to hold the cam plate on the body. The body has a rearward cylindrical extension, a, through which two diametrically opposed 60 longitudinal slots a', a' are formed, which slots extend as grooves to the front end of the body in the enlarged end or head a thereof, and through the cap D. Embracing this cylindrical portion a is a ring E. 65 A bar G extends across the tubular center of the body, and its rearwardly turned side members g lie and move in said slots and grooves; and their rear ends are connected rigidly with the ring E. It is clear 70 that, although the ring E may move longitudinally upon the body, it cannot turn thereon, being prevented by the parts g in the grooves a'. On this ring is a laterally extended wing e in which is an arc-shaped 75 slot e'. An inclined bar J passes through but is non-rotatable in this slot, and is capable of being moved along the slot to any desired position; and it may be clamped to the ring E in any position by means of the 80 clamping nut K having the handle k. The front end of this rod passes through a hole in the laterally extended ear e of the cam plate C. It is obvious that if the ring be moved longitudinally upon the body, this 85 rod will, because of its inclination, turn the cam plate in one direction or the other, depending upon the direction in which said ring is moved. When the ring is moved toward the front end of the head the cam 90 plate will be turned in that direction which causes the outward or receding movement of said dies. At the rear end of the head are the radially movable guide bars H operated 95 by a cam plate I of familiar form. There is nothing novel at this end of the die stock and any of the well known guide devices employed in die stocks may be used in place of those shown.

In using the die stock it is placed on the 100 work. The guide bars H are moved so as to center the die stock on the work. The clamping nut K is loosened, and the cam plate C is then turned so as to bring the dies in proper position to cut the thread upon 105 said work. The ring E at this time has been moved rearward on the body, and preferably against the shoulder a' thereon. After a suitable length of the thread has been cut, during the cutting of which the 110

die stock will advance upon the work, the bar G will come into contact with the end of the work. As the die stock now continues to turn and advance this bar cannot 5 advance with it and, therefore, since it is connected with the ring E, said ring will move relatively forward upon the die stock body. This will cause the inclined bar J to move through the hole in the ear of the cam 10 plate and this will cause the cam plate to turn in the direction indicated by the arrow in Fig. 1, and this will cause the dies to recede.

It will be noted that the front end of the 15 inclined bar J is enlarged, the enlargement or head *j* being set eccentrically on the end of said bar, so that the surface of said head and the surface of the bar on one side of the latter are alined. When this bar moved 20 by ring E is moved far enough, the enlarged head *j* will have passed through the hole in the cam plate ear, and therefore the cam plate may now be turned a distance sufficient to entirely withdraw the dies from 25 the work. To restore the parts to the starting point and particularly to enable the ring E to move back against the shoulder α^3 , the cam plate is turned until one side of the 30 hole in its ear engages with that side of the bar J which is alined with the corresponding side of the head *j*. This being done, the ring E may be pushed backward and the head *j* will slip smoothly into and through the hole in said cam plate ear.

35 The return of the parts to their normal positions as described may be facilitated, and the parts may be held in such position while the device is being handled, by a spring or springs, as, for example, con- 40 tractile coil springs M. In the construction shown one end of each spring is attached to the rear end of the die stock body. In the construction shown the rear ends of the springs are attached to the body by means 45 of screws P which are primarily provided for connecting two parts of the body together. The front ends of the spring pass through the ring and engage pins N which are fixed to the ring.

50 Having described my invention, I claim:
1. In a die stock, the combination of a

body having a head and cylindrical portion behind said head, there being through said cylindrical portion two diametrically opposed longitudinal slots which are extended 55 as grooves in the head part of said body to the front end thereof, radially movable dies mounted in the end of said head, and a cam plate rotatably mounted on said head and engaging said dies and having a laterally 60 extended perforated ear, the ring embracing the cylindrical part of said body, an inclined bar connected therewith and extended through said perforated ear, and a bar ex- 65 tends across the tubular center of said body and having rearwardly extended mem- bers which pass through said longitudinal slots and are fixed to said ring.

2. In a die stock, the combination of a 70 body, radially movable dies carried thereby, a cam plate mounted on the body and en- gaging said dies and having a laterally ex- 75 tended perforated ear, a ring longitudinally movable upon said body, means preventing its rotation, and an inclined bar fixed to said ring and extended through said perforated ear, said bar having at its front end an en- 80 larged head offset to one side of said bar so that at the opposite side the external sur- 85 faces of said head and bar are in the same plane, and a bar fixed to said ring and ex- 90 tended across the tubular center of the body.

3. In a die stock, the combination of a 95 body having a longitudinal slot, radially movable dies mounted on said body, a ro- tatable cam plate mounted on the body and en- gaging said dies to move them, a ring in- 90 movable longitudinally on said body and having an inclined surface engaging with a part of said cam plate, a bar extending across the tubular center of said body and through the slot therein and being connected with said ring, and a spring connected with the ring and body and exerting its force to draw the ring rearward on the body.

In testimony whereof, I hereunto affix my signature in the presence of two witnesses.

HERMAN W. OSTER.
